UNITED STATES PATENT OFFICE.

FRED ROEGER, OF HASBROUCK HEIGHTS, NEW JERSEY, ASSIGNOR OF ONE-HALF TO
HOWARD S. NEIMAN, OF NEW YORK, N. Y.

MEMORANDUM PAD.

Application filed November 12, 1925. Serial No. 68,584.

My invention relates to memorandum pads and refers particularly to devices of this character in which the reverse sheets of the pad can be retained within the pad after use.

5 The value of memorandum, or diary, sheets in pad form is widely recognized and the additional value of means for retaining those sheets which have at least temporarily served their usefulness is evident.

10 This purpose has been accomplished by means of blank books or of pads of paper sheets which open similarly to books.

Both of these forms of memorandum blanks have objectionable features which are 15 overcome by the device of my invention.

My invention relates to a pad of paper sheets removable from and replaceable in a cover, having all of the desirable attributes of a blank book in that the used sheets are 20 made a permanent part thereof, if desired, the device occupying less space upon a desk than the known paper pads having permanent recording means.

The device of my invention possesses other 25 valuable features as will be evident upon a consideration of my specification and accompanying drawings.

The object of my invention is a pad of paper sheets in which the top sheet is exposed for purposes of information or for recording, the top sheet when it has served its 30 purpose being placeable at the bottom of the pad, thus exposing a new top sheet, the whole being removably carried within a book cover.

35 In addition to thus furnishing a means of permanent record, the particular construction allows of a pad of permanent thickness, thus causing the top and bottom elements of the cover to always be in proper parallel plane position with respect to each other, which is 40 not possible in those memorandum pads in which the used sheets are removed.

The novelty and usefulness of the device 45 of my invention are illustrated in the following description and explanation.

In the accompanying drawings illustrating modified forms of the device of my invention similar parts are designated by similar numerals.

50 Figure 1 is a perspective view of one form of the device of my invention in open position.

Figure 2 is a cross-section through the line 2-2 of Figure 1.

Figure 3 is a perspective view of the cover 55 shown in Figure 1.

Figure 4 is a perspective view of the pad of sheets and connecting rings shown in Figure 1.

Figure 5 is the binder shown in Figure 1 60 removed from the pad and in open position.

Figure 6 is a modified form of binder shown in combination with a pad of sheets.

Figure 7 illustrates a step in the transference of a sheet from the top to the bottom 65 of the pad.

Figure 8 illustrates a continuation of the transference of a sheet from the top to the bottom of the pad.

Figure 9 is a top plan view of a modified 70 form of my device in open position.

Figure 10 is an enlarged cross-section through the line 10-10 of Figure 9, the cover being closed.

Figure 11 is a perspective view of the 75 binder shown in Figure 9 in open position.

Figure 12 is a perspective view of the connecting rings shown in Figure 9 in open position.

Figure 13 is a perspective view of a pad 80 of paper sheets shown in Figure 9.

The particular form of the device of my invention shown in Figures 1 to 5 inclusive comprises a hinged cover consisting of the bottom member 15 and the top member 16 made of stiff cardboard or other suitable material. The top and bottom members are connected by the two flexible cloth, or paper, members 17 and 18, fixedly attached thereto but allowing of a space, or passage, 19 between those portions between the bottom member 15 and the top member 16. For the sake of appearance, a cover of leather or paper 20 may be attached to and cover the entire outside of the device. 95

A pad of paper sheets 21, having dates or other desirable printed matter thereon, has two perforations 22, in one end portion thereof, and the sheets are connected by two elongated ring members 23, 23. For convenience of operation, the two rings 23, are somewhat longer than the height of the pad. The pad has a cutout for purposes disclosed later. 100

A binder 24, made of aluminium or other suitable material has one end shouldered 25 and prolonged into a pointed member 26, capable of placement through the opening

27 of the other end portion of the binder. The binder 24 is passed through the opening 19, around the pad 21 and within the rings 23, 23. The pointed portion 26 is then passed through the opening 27 and the whole held in closed position by the portions 28, 28 of the pointed member snapping into the small recesses 29, 29 of the shoulder 25.

The operation of the device is shown in Figures 7 and 8. When the top sheet of the pad 21 has served its purpose and it is desired to place it beneath the pad, the device is opened as shown in Figure 7, the top page raised to the position A and passed over the rings 23, 23 to the position B. The pad is then raised to the position shown in Figure 8, the page which is then in the position C is moved as D to the bottom of the pad, placed thereon and the pad revolved back to its original position. The cut-out 30 enables ready access to the top sheet of paper for purposes of operation.

It is to be noted that in the described construction re-fill pads may be marketed in the form of the pad with the connecting rings already inserted and the binder thereon. In order to attach the pad to the cover, the binder can be passed through the opening 19 and locked around the pad.

In the modified form of my device shown in Figure 6, the binder 24 is reversed in position from that previously described, the open ends being inserted within the opening 19 of the cover and retained therein by the resiliency of the material from which it is made.

In the modified form of my device shown in Figures 9, 10, 11, 12 and 13, the connecting rings are formed of two telescopic members 31 and 32 and the binder comprises two elements 33 and 34 capable of being placed in locked position. In the particular construction of binder thus shown, one element 34 has reduced pointed end members 35, 35 having recesses 36, 36. The element 33 has its extremity sides 37, 37 bent over to produced a sliding guide for the members 35, 35 and has inwardly directed points 38, 38 to enter the recesses 36, 36 and maintain the two elements in locked position. In the modification thus shown, the bottom 15 and the top 16 have recesses 39, 39 and 40, 40 to receive the rings 31-32, 31-32 and thus allow the pad 21 to rest flush with the inside faces of the bottom and top.

In the modification last described, the connecting rings and the binder are re-usable and, hence, the refill would consist of a pad of loose sheets 40 as shown in Figure 13.

It is also to be noted that in this modification of my device any particular sheet can be removed from the pad without disturbing the arrangement of the other sheets.

It will be seen from the above that my invention comprises a pad of memorandum, or

other, sheets of paper within a hinged cover, so constructed and arranged that successive top sheets may be placed upon the bottom of the pad, thus retaining the entire collection of sheets, allowing a new one for use and maintaining the whole within the cover. 70

It is evident that there may be variations in the device of my invention from the particular modifications described, and hence, I do not limit myself to the particular size, 75 shape, number, arrangement or material of parts as shown and described as these are given simply as a means for clearly describing the device of my invention.

What I claim is:—

1. In a memorandum device, in combination, a hinged cover, said cover having a back portion and two cover portions, a recess within the back portion open at both ends thereof, ring means for connecting the sheets of a pad of paper, and a binder positioned around the sheets and within the cover recess. 80

2. In a memorandum device, in combination, a hinged cover, said cover having a back portion and two cover portions, a recess within the back portion open at both ends thereof, a plurality of rings for passing through perforations in one end portion of a pad of sheets for maintaining them in pad form and a removable flat binder capable of being placed around the edges of the sheets and within the cover recess. 90

3. In a memorandum device, in combination, a hinged cover, said cover having a back portion and two cover portions, a recess within the back portion open at both ends thereof, a plurality of rings for passing through perforations in one end portion of a pad of sheets for maintaining them in pad form and a removable flat metallic binder capable of being placed around the edges of the sheets and within the rings, the binder being insertable within the cover recess. 100

4. In a memorandum device, in combination, a hinged cover, said cover having a back portion and two cover portions, a recess within the back portion open at both ends thereof, a plurality of wings for passing through perforations in one end portion of a pad of sheets for maintaining them in pad form, a removable flat binder capable of being placed around the edges of the sheets and within the rings and insertable within the cover recess, the ends of the binder being capable of lockment with each other when so positioned. 110

5. In a memorandum device, in combination, a hinged cover, said cover having a back portion and two cover portions, a recess within the back portion open at both ends thereof, a plurality of separable rings for passing through perforations in one end portion of a pad of sheets for maintaining 125

them in pad form and a separable flat binder capable of being placed around the edges of the sheets and within the rings, the separable binder members being capable of lock-

5 ment with each other when so positioned.

6. In a memorandum pad, in combination, a plurality of ring means for maintaining a plurality of sheets in pad form and an openable binder extending around 10 the edges of the sheets and within the rings.

7. In a memorandum pad, in combination, a plurality of ring means for maintaining a plurality of sheets in pad form, an openable binder extending around the 15 edges of the sheets and within the rings and means for locking the binder in closed position.

8. In a memorandum pad, in combination, a bottom member, an end member flexibly 20 attached to the bottom member, a binder carried by said end member adapted to extend around the edges of a plurality of sheets and means for maintaining the paper

sheets in pad form whereby the top sheet is placeable at the bottom of the pad without 25 removal of the binder from said end member.

9. In a memorandum pad, in combination, a binder for extension around the edges of a pad of sheets and means for connecting 30 said sheets to the binder so formed and positioned that the top sheet is transferable to the bottom of said pad without separating the sheets from said binder.

10. In a memorandum pad, in combination, a flat binder for extension around the edges of a pad of sheets and means for connecting 35 said sheets to the binder so formed and positioned that the top sheet is transferable to the bottom of said pad without 40 separating the sheets from said binder.

Signed at New York city in the county of New York and State of New York this 9th day of November, 1925.

FRED ROEGER.
